UNITED STATES PATENT OFFICE.

MARIUS METHILTUS SÖRENSEN, OF VALLERÖD, NEAR RUNGSTED, DENMARK.

APPLIANCE FOR RIFLING THE MARGIN OF THE SOLE OF FOOTGEAR.

1,376,474.

Specification of Letters Patent.

Patented May 3, 1921.

Application filed October 3, 1919. Serial No. 328,140.

To all whom it may concern:

Be it known that I, MARIUS METHILTUS SÖRENSEN, a subject of the King of Denmark, residing at Valleröd, near Rungsted, 5 isle of Sealand, in the Kingdom of Denmark, have invented certain new and useful Improvements in Appliances for Rifling the Margin of the Sole of Footgear, of which the following is a specification.

10 The rotating appliance generally used for rifling the margin of the sole of footgear has, on its periphery, a series of projections much resembling the cogs on a conical cog-wheel, and, by using this appliance, the pro- 15 file of its periphery is "developed" along the margin of the sole by means of simple pressure-effect.

This invention refers to a rotating rifling-tool which, unlike that already known, does 20 not act entirely by means of pressure, but also has a sliding or polishing effect, since the movement taking place between the sole and the tool principally occurs transversely to the longitudinal direction of the edge of 25 the sole.

One form of construction is, by way of example, diagrammatically shown on the drawing in Figure 1, which is a side-view, and Fig. 2, which is a front view.

30 The tool here shown is a wheel 3 with single or multiple screw-thread 4 on its periphery. The size and form of the screw-thread in section corresponds to the desired rifling. The wheel is disposed on a rotat- 35 ing shaft, axle, mandrel, or the like, and the margin of the sole 5, which is not yet connected with the upper, is held pressed against its periphery. The screw-thread will then be impressed into the margin of 40 the sole, which is thereby rifled. At the

same time, the wheel can be moved along the margin of the sole, or, if the underlying surface upon which the sole rests is movable, the wheel may itself carry the margin of the sole forward.

The form of construction here shown is, as already said, merely an example, and it can be modified and altered in many different ways. Instead of one or more rotating entire wheels, there may be used one or more 50 segments, which rotate or oscillate back and forth. The projections that do the rifling do not need to be continuous as is the case in screw-threads or to have the shape of continuous ribs, but may be more or less 55 interrupted. The main feature of the invention is, in general, only that each separate rifle, *i. e.*, each separate depression in the leather, is gradually formed by the action of several consecutive parts of the same 60 projection as it moves in the longitudinal direction of the depression, thus at a right angle or approximately at a right angle to the margin of the sole. In accordance with this method, each projection has the shape 65 of an arc or eventually an entire circle, with its center in or approximately in the axis of revolution.

I claim:—

A rotating tool for rifling the margin of 70 the sole of footwear, having a projection on its periphery in the shape of a screw-thread.

In testimony whereof I affix my signature in the presence of two witnesses.

MARIUS METHILTUS SÖRENSEN.
